UNITED STATES PATENT OFFICE.

GUSTAV A. FAITZ, OF CHICAGO, ILLINOIS.

RATCHET WRENCH.

Application filed August 10, 1921. Serial No. 491,182.

To all whom it may concern:

Be it known that I, GUSTAV A. FAITZ, a citizen of the United States, and resident of Chicago, county of Cook and State of Illinois, have invented certain new and useful Improvements in Ratchet Wrenches, of which the following is a specification, and which are illustrated in the accompanying drawings, forming a part thereof.

10 The invention relates to wrenches and more particularly to those having a socket for application to the member to be rotated, and ratchet mechanism permitting a reverse movement of the handle without corresponding movement of the socket. The object of

15 the invention is to provide a ratchet wrench comprising only a small number of parts but capable of use without change for the application of power in either direction.

20 The invention is exemplified in the structure to be hereinafter described and which is illustrated in the accompanying drawings, in which;

25 Fig. 1 is a plan view of the improved wrench showing only a part of the handle;

Fig. 2 is similar to Fig. 1, but with one of the side plates of the head removed and one of the connecting bolts shown in section;

30 Fig. 3 is a detail view principally in central longitudinal section showing the parts of the wrench disassembled, a nut to which the wrench socket may be applied and the connecting nuts and bolts being shown in elevation;

35 Fig. 4 is a plan view of the wrench with the parts in operative position for rotation of a nut in the direction indicated by the arrow, one of the side plates of the wrench head being partly broken away and one of the connecting bolts being shown in section, and

40 Figs. 5, 6 and 7 are each similar to Fig. 2, but show modified forms of construction.

45 As is usual in the construction of ratchet wrenches, the improved wrench comprises a swinging handle 10, and a head generally designated 11, to which the handle 10 is pivotally attached as by a connecting bolt 16.

50 For convenience of construction the walls of the head 10 will preferably include a pair of side plates shown at 12 and 13, the two side plates being shown as being formed with inturned marginal flanges 26, 27, which serve to separate the plates in all

other parts of the same a sufficient distance 55 to receive the adjacent part of the handle 10 between them. The pivot bolt 16 accordingly serves to connect the side plates and a second bolt 17 provides both an additional connecting means and a stop for limiting 60 the swinging movement of the handle 10, as in Fig. 4. To avoid interference with the movement of the handle by pressure of the side plates against the same, a spacing bushing 36 (Fig. 3) is preferably mounted on 65 the pivot bolt 16 while the bolt 17 is desirably formed with a limiting shoulder 37.

The improved wrench is also of ordinary construction in that it includes a ratchet hub 20 which is centrally apertured to receive the 70 squared stem 25 of a bolt or nut socket 24. As usual, the ratchet hub 20 is located between the side plates 12, 13, and its two rounded ends, as 21 project through and are journaled in the corresponding side plates, 75 thereby permitting the introduction of the stem 25 of the socket 24 from either side of the wrench.

In carrying out the invention, pawls, as 14 and 15, 30 and 31 or 34, are provided for 80 actuating the ratchet hub 20 in either direction and these pawls are positioned by the movement of the handle 10. In Figs. 1 to 5 and in Fig. 7 the pawls 14, 15 or 34 are formed integral with the handle 10 while 85 in Fig. 6 the pawls 30, 31 are formed together as a separate piece which is pivotally mounted on the connecting bolt 17 and the handle 10 is provided with lugs 32, 33, at its inner end. These lugs embrace the said 90 separate pawl member between them and engage the same upon movement of the handle in either direction for advancing the corresponding pawl.

Since, in every case, the positioning of the 95 pawls is accomplished by the swinging of the handle 10, it follows that movement of the handle in the direction in which power is to be applied, as in Fig. 4, serves to advance the proper pawl, as 14, for turning the 100 ratchet hub 20 in the desired direction. To avoid engaging the other pawl, as 15, during idle movement of the handle in the opposite direction it is only necessary to grasp the handle in such a way as to impart the 105 said idle movement to the same without substantial turning movement of the handle on the pivot bolt 16. On the other hand, if the

application of power in the said opposite direction is desired this is readily accomplished by merely swinging the handle in that direction.

5 In each of the forms of construction illustrated in Figs. 5, 6 and 7, the said manual control of the swinging movements of the handle is facilitated by the provision of leaf springs 28, 29, which tend to maintain 10 the handle in central position. These springs are applied to the walls of the wrench head upon the inside of the same and embrace the corresponding pawls between them. For the application of power in 15 either direction it is necessary to swing the handle upon the pivot bolt 16 against the resistance of the springs while the springs facilitate the making of an idle movement of the handle without turning the same upon 20 the pivot pin 16 beyond the central position of the handle with respect to the wrench head. The construction illustrated in Fig. 7 is identical with that illustrated in Fig. 5 except that the pawls 34 are each formed 25 with a series of teeth and the ratchet hub 20 is provided with correspondingly shaped ratchet teeth.

I claim as my invention:—

1. In a ratchet wrench, in combination, a head comprising a pair of parallel plates 30 having inwardly projecting spacing flanges at their peripheries, a sleeve journaled between the plates, ratchet teeth formed on the sleeve, a handle pivoted between the plates, a pair of oppositely facing pawls fixed to the handle and projecting beyond the pivot of the handle to cooperate with the ratchet teeth, and springs mounted within the head reacting upon the handle for normally holding 40 the handle in central position.

2. In a reversible ratchet wrench, in combination, a head comprising a pair of parallel plates having inwardly projecting spacing flanges at their peripheries, a ratchet sleeve journaled in said plates, ratchet teeth 45 formed on the sleeve between the plates, said teeth having two oppositely directed sets of pawl engaging faces, a handle pivoted between the plates, a pair of pawls operated by said handle and each adapted to cooperate with one set of pawl engaging faces on said ratchet teeth for rotating said sleeve 50 in a given direction.

GUSTAV A. FAITZ.
